Patented June 27, 1922.

FIG. I

FIG. II

FIG. III

Inventor
Arthur D. Smith
By *Elie Oscar*
Attorney

UNITED STATES PATENT OFFICE.

ARTHUR D. SMITH, OF PORTLAND, MAINE, ASSIGNOR TO NATIONAL SEAL COMPANY, INC., OF NEW YORK, N. Y., A CORPORATION OF NEW YORK.

CLOSURE FOR CONTAINING VESSELS.

1,420,768.

Specification of Letters Patent. Patented June 27, 1922.

Application filed May 15, 1920. Serial No. 381,584.

To all whom it may concern:

Be it known that I, ARTHUR D. SMITH, a citizen of the United States, residing at Portland, county of Cumberland, State of Maine, have invented certain new and useful Improvements in Closures for Containing Vessels, of which the following is a specification.

This invention relates to closures for containing vessels, and particularly to a metallic closure adapted to hermetically seal vessels containing highly volatile preparations which rapidly deteriorate upon contact with the atmosphere. In such closures it is customary to employ a fibrous pack which is adapted to be compressed over the mouth of the closure in the application of the closure to the vessel.

This pack has been usually glued in position within the cap, and before the pack could be applied, it was necessary to remove the film of palm oil or other protective agent with which the sheet metal caps have been treated. This was usually done by washing the sheet metal in a solution of hot water and caustic soda and then drying in suitable driers. The washing and drying steps not only involve a loss of time and labor, but where the cap is insufficiently dried the dampness soon penetrates the glued pack, causing the paper of the pack to bulge and producing an element of uncertainty of seal. Moreover, the varying conditions of temperature in the factory itself affect the glued paper pack, causing shrinkage or expansion.

To the end therefore of eliminating the use of the glued pack I have devised my present invention in which the pack is positively held in place by the formation of the cap itself. My invention not only avoids the use of glue but obviates the necessity of washing and drying the caps to remove the surface film, thus eliminating those factors which made for loss of time, and uncertainty of seal. In carrying out my invention I positively retain the pack in position by a reduction of the internal diameter of the cap itself whereby to lock the pack therein.

As illustrative of my invention I have shown in somewhat exaggerated scale in the

accompanying drawings a cap and interlocked pack, constructed in accordance with my invention. In the drawings:

Fig. I is an enlarged section showing the cap before the pack has been interlocked therein, and

Fig. II shows the cap after the pack has been interlocked therein by slightly reducing the skirt of the seal, the reducing operation being indicated diagrammatically by the arrows A in said figure, and

Fig. III is an enlarged detail particularly illustrating the interlock of a cap and pack.

My invention may be performed as a single and continuous operation as distinguished from the several operations and intervals of washing and drying, which characterize the use of the glued pack.

The closure or seal consists of a cap having a top surface 1 which is drawn about its periphery to provide an annular depending skirt or rim 2 having integral lugs or fingers 3 adapted for interlocking engagement with the vessel to position the seal over the mouth thereof. The pack 4 which may be of paper, or other fibrous composition, is adapted to be inserted against the inner face of the top surface 1 and in its final condition to snugly fit within the annular skirt 2 of the cap, being interlocked therewith.

In carrying out my invention the skirt 2 is drawn with an internal diameter slightly larger than the maximum external diameter of the pack 4 so that the pack may be readily inserted within the cap, as appears in enlarged section, Fig. I.

In practice the difference in diameters need be only a few ten-thousandths of an inch. The pack is then inserted within the skirt 2, and the skirt reduced down as far as the outer face of the pack (see dotted line showing of Fig. III) to restore the skirt to substantially its original or intended diameter, as indicated in Fig. II, wherein the arrows A diagrammatically represent the reducing operation. This reducing operation clamps the pack snugly in place within the cap, as clearly shown in Fig. III, wherein the pack and skirt are shown as interlocked with each other. This engagement is further enhanced by the annular bead 5 of the

cap which is compressed into the inner face of the pack, (see Fig. III) and assists to prevent dislodgement of the pack from the cap.

Various modifications in the form and construction of my closure may obviously be resorted to within the limits of the appended claims.

What I therefore claim and desire to secure by Letters Patent is:

- 10 1. A metallic cap having an annular groove in its marginal top surface, and a compressible pack abutting the entire inner face of the cap top, said cap having a normal maximum internal diameter slightly
- 15 greater than the normal maximum external diameter of the pack, said cap being slightly

reduced circumferentially opposite the edges of said pack to yieldingly clamp the rim of the pack between the cap and said groove.

2. A metallic cap having an annular peripheral groove in its top surface and having a pendent skirt, a compressible pack abutting the entire inner face of the cap top, said skirt having a normal maximum internal diameter slightly greater than the normal maximum external diameter of the pack, said skirt being slightly reduced circumferentially opposite the edges of said pack to yieldingly clamp the rim of the pack between the skirt and said groove.

In testimony whereof I affix my signature.

ARTHUR D. SMITH.
